[57] CLAIM

The ornamental design for a transducer connector case, as shown.

DESCRIPTION

FIG. 1 is the front isometric view of the transducer connector case design of the invention;

FIG. 2 is the rear isometric view of the transducer connector case design of the invention;

FIG. 3 is the left view of the transducer connector case design of the invention;

FIG. 4 is the top view of the transducer connector case design of the invention;

FIG. 5 is the front view of the transducer connector case design of the invention;

FIG. 6 is the bottom view of the transducer connector case design of the invention;

FIG. 7 is the right view of the transducer connector case design of the invention; and,

FIG. 8 is the back view of the transducer connector case design of the invention.
